UNITED STATES PATENT OFFICE

IVAN E. BEELER, OF SAN FRANCISCO, CALIFORNIA

DOOR CLOSER

Application filed May 18, 1931. Serial No. 538,310.

This invention relates to certain new and useful improvements in door closing devices and more particularly to one which is designed for use in conjunction with swinging doors to automatically return same from either of its open positions to that of a closed position.

With the above and other objects in view, the invention further consists of the following novel features and details of construction, to be hereinafter more fully described, illustrated in the accompanying drawing and pointed out in the appended claim.

In the drawing:

15 Figure 1 is a fragmentary elevation of a door frame and mounting for a swinging door, disclosing by full and dotted lines the relative arrangement of the several connections of the present invention therewith.

20 Figure 2 is a longitudinal sectional view taken through a portion of the winding drum and illustrative of the retracting element.

Figure 3 is a sectional view taken through the drum showing the relative arrangement 25 of the spring element.

Figure 4 is a bottom plan view of the invention.

Figure 5 is a sectional view taken on line 5-5 of Figure 2.

30 Referring to the drawing in detail wherein like characters of reference denote corresponding parts, the reference character 10 indicates generally the upper rail of a door frame 11 having a door 12 therefor swingably supported within the door opening upon pintles 13 embedded in the upper rail and sill respectively.

35 All of the above is of the usual and well known construction incidental to that of 40 door mountings and forms no part of the present application for letters patent but are mentioned merely for purposes of illustration in bringing forward the novel advantages of the present invention.

45 The invention primarily resides in the provision and arrangement of an elongated box like housing 14 projecting upwardly through an opening provided in the upper rail 10 of the door frame and provided with attaching flanges 15 recessed or otherwise mortised

within the surface thereof whereby the normal swinging motions of the door will be unimpaired.

A pin member 16 wholly disposed within the confines of the box like housing 14, terminates to provide heads 17 engageable with the outer surfaces and side walls of said housing. A spring element, generally designated as at 18, of the Archimedian spiral type, has its outer end secured to a shaft 19; the latter being supported between the walls of the housing at a point above and in spaced parallelism with the shaft or pin member 16. The innermost end of the spring is fixed to a drum member 16' in the manner suggested in Figure 3 of the drawing.

55 Roller members 20 journaled in spaced parallelism provide a guide passage 21 therebetween through which a flexible member 22 is passed. Said flexible element is wound about the drum member 16' and fixed at one end therewith as shown in Figure 2. The other end of the flexible connecting element is connected with a screw eye 23 disposed within a recess 24 located in the upper rail 70 of the door 12.

60 As understood from the foregoing description and accompanying drawing the spring element 18 will yieldably induce the door to occupy a normally closed position irrespective of whether the door is actuated from either side. The roller members 20 will materially enhance the life and facilitate smoother action on the part of the flexible connecting element whereby the door may be 75 actuated in the manner contemplated with a minimum degree of wear.

65 The attaching flange 15 carries headed studs 25 upon opposite sides of the entrance for the housing which depend therefrom to 80 journal support disk members 26 arranged at right angles to the roller members 20. These disk members are designed for engagement with the flexible member 22 to prevent chafing of the latter against the edges 85 of the recess 24. As shown in Figures 1 and 2 of the drawing, the disk members are projected within the recess 24 to clear the door when the latter is swung to either side of the door frame.

The invention is susceptible of various changes in its form, proportions and minor details of construction and the right is herein reserved to make such changes as properly fall within the scope of the appended claim.

Having described the invention, what is claimed is:

A door closing apparatus comprising a housing located within the upper portion of a door frame, a drum member journaled within the housing having a spiraled spring connected therewith, an attaching element upon the upper rail of the door, roller members journally supported within the housing and spaced apart to provide a guide passage therebetween, a flexible connecting element fixed to and wound upon said drum member and projecting through the passageway for connection with the attaching element, and disk members journaled upon the housing in rightangularly disposed relation to the roller members for engagement with that portion of said flexible connecting element projecting through the passageway.

25 In testimony whereof I affix my signature.
IVAN E. BEELER.
